UNITED STATES PATENT OFFICE.

GEORGE W. NEIBLE, OF CHESTER, PENNSYLVANIA.

COMBINED GARMENT-SUPPORTER AND HOOK.

SPECIFICATION forming part of Letters Patent No. 625,189, dated May 16, 1899.

Application filed January 14, 1899. Serial No. 702,183. (No model.)

To all whom it may concern:

Be it known that I, GEORGE W. NEIBLE, a citizen of the United States, residing at Chester, in the county of Delaware and State of Pennsylvania, have invented new and useful Improvements in a Combined Garment-Supporter and Hook, of which the following is a specification.

My invention relates to a combined garment-supporter and hook and eye adapted to be secured to the waistband of a pair of trousers, a skirt, or other garment and connected with a waist-belt in such a manner that the garment may be supported and the ends of the waistband thereof be connected with each other.

The invention consists in a hook made from a single piece of wire having one end bent into a loop by which it may be secured to a waistband, then extended upwardly and then bent outwardly, forming a hook adapted to engage with a waist-belt, then extended downwardly and then laterally, forming a hook at a right angle to said first-mentioned hook, adapted to be engaged with an eye secured to the waistband, and then bent into a loop by which it may be secured to a waistband, as hereinafter fully described and claimed.

In the accompanying drawings, Figure 1 is a perspective view showing my invention applied to a pair of trousers, looking from the outside. Fig. 2 is a plan view showing the invention applied to a pair of trousers and connected with a waist-belt. Fig. 3 is a perspective view of the hook detached. Fig. 4 is a front view showing my invention applied to a waist-belt.

In the said drawings the reference-numeral 1 designates the flap of a pair of trousers. The numeral 2 designates the hook, consisting of a single piece of metal having one end bent into a loop by which it is secured to the waistband 3. The wire is then extended upwardly, forming a vertical arm 4, and then bent downwardly and then upwardly, forming a curved hook 5, and then downwardly,

forming a vertical arm 6. The wire is then bent outwardly and then inwardly, forming a hook 7, and the extremity formed into a loop for securing this end to the waistband. 50

The numeral 8 designates an ordinary eye connected with the opposite end of the waistband.

The numeral 9 designates a waist-belt of any ordinary or suitable construction. 55

In practice the hook proper is secured to the waistband, near one end thereof, and the eye to the opposite end thereof. The hook 5 is then engaged with the upper edge of the waist-belt, by which the garment will be suspended. The eye is then engaged with the hook 7, closing the flaps. 60

While I have shown the invention applied to a pair of trousers, it can be used with a skirt or other article of wearing-apparel. 65

Having thus fully described my invention, what I claim is—

1. As an improved article, a combined garment-supporter and hook, consisting of a single piece of wire, the ends of which are bent into loops, and then extended upwardly forming two arms, one of which is bent into a hook and the portion intermediate said arms bent into a curved outwardly-extending hook, substantially as described. 75

2. The combination with a garment-supporter comprising a single piece of wire having the ends bent into loops and then extended upwardly forming two arms, one of which is bent to form a longitudinal hook and the portion intermediate said arms bent to form an outwardly-extending curved hook, of the eye adapted to be connected with said first-mentioned hook, substantially as described. 80

In testimony whereof I have hereunto set my hand in presence of two subscribing witnesses.

GEORGE W. NEIBLE.

Witnesses:

E. A. PENNELL,
ANNA M. MCGINLEY.
